US0D1076963S

(12) **United States Design Patent** (10) Patent No.: **US D1,076,963 S**
De Luca et al. (45) Date of Patent: ** May 27, 2025

(54) **DISPLAY SCREEN WITH GRAPHICAL USER INTERFACE**(71) Applicant: **Google LLC**, Mountain View, CA (US)(72) Inventors: **Matthew De Luca**, New York, NY (US); **Manini Roy**, Seattle, WA (US); **Edward Leung Chui Jung**, London (GB); **Shane Harley**, Los Angeles, CA (US)(73) Assignee: **GOOGLE LLC**, Mountain View, CA (US)(***) Term: **15 Years**(21) Appl. No.: **29/878,632**(22) Filed: **Jun. 26, 2023**(51) LOC (15) Cl. **14-04**

Primary Examiner — Daniel J Domino*Assistant Examiner* — Ana M. Vine(74) *Attorney, Agent, or Firm* — Plumsea Law Group, LLC(57) **CLAIM**

The ornamental design for a display screen with graphical user interface, as shown and described.

DESCRIPTION

The sole FIGURE is a front view of a display screen with graphical user interface showing the new design.

The outermost dash-dash broken lines showing an electronic device illustrate environmental subject matter and form no part of the claimed design. The dot-dash broken lines showing a display screen and dash-dash broken lines within the dot-dash broken lines showing portions of the graphical user interface illustrate portions of the article and form no part of the claimed design.

1 Claim, 1 Drawing Sheet(56)
